UNITED STATES PATENT OFFICE.

ERNEST BERTRON, OF BRUSSELS, BELGIUM.

SIGN LUMINOUS BY REFLECTION.

1,400,855.

Specification of Letters Patent. Patented Dec. 20, 1921.

Application filed February 25, 1920. Serial No. 361,188.

(GRANTED UNDER THE PROVISIONS OF THE ACT OF MARCH 3, 1921, 41 STAT. L., 1313.)

To all whom it may concern:

Be it known that I, ERNEST BERTRON, citizen of the Republic of France, residing at 60 Square Francois Riga, Brussels, in the 5 Kingdom of Belgium, have invented new and useful Improvements in Signs Luminous by Reflection, for which applications have been filed in foreign countries as follows: in Belgium, May 28, 1914; in France, 10 June 30, 1914; in Spain, Aug. 1, 1918, and Italy, May 23, 1919, and of which the following is a specification.

The present invention relates to the production of signs, letters and generally speaking 15 of designs of all kinds which are rendered luminous by reflection. By means of the said process, it is possible to obtain the illumination of inscriptions or other signs without consumption of light of any kind 20 and in a simple and economical manner.

The invention is shown by way of example on the annexed drawing in which:

Figures 1 and 2 are respectively a section and a front view of a form of execution of 25 said invention and

Fig. 3 is a section of another form of execution.

In order to carry the invention into practice, signs made of any suitable material 30 are formed by pouring said material, such as staff, paste board, stone, plaster, etc., into suitable molds in order to obtain signs reproducing in relief the inscriptions or designs desired.

35 Pastilles or disks of any desired outline, preferably made of glass, and gilt or silvered are applied on the signs so made by means of any suitable adhesive material, said disks being concave or convex.

40 Figs. 1 and 2 show an application of convex glass disks. According to this form of the invention, the sign 1 carries the convex glass disks 2 which may be cemented on projections in relief 4 provided on the sur-

face of the sign at the points where the 45 disks are to be placed, the projecting rounded form of the reliefs corresponding to the hollow form of the disks.

Fig. 3 shows an application of concave disks 3 according to which the disks are located in recesses or depressions 5 provided in the body of the sign 1.

It is also possible to devise other means for utilizing concave or convex luminous disks of the kind above described in order 55 to form signs or inscriptions, without departing from the spirit of the invention.

Having now described my invention, what I claim as new and desire to secure by Letters Patent is:

1. A luminous sign comprising a molded sign body having seatings formed thereon in the molding operation and thin, metal coated cup shaped disks cemented on said seatings and arranged to form the outlines 65 of the characters constituting the luminous sign.

2. A luminous sign comprising a molded sign body having rounded projections formed thereon in the molding operation 70 and thin, metal coated, cup shaped disks cemented on said rounded projections and arranged to form the outlines of the characters constituting the luminous sign.

3. A luminous sign comprising a molded 75 sign body having rounded projections formed thereon in the molding operation and thin, metal coated, cup shaped, glass disks cemented on said rounded projections and arranged to form the outlines of the 80 characters constituting the luminous sign.

In testimony whereof I have signed my name to this specification in the presence of two subscribing witnesses.

ERNEST BERTRON.

Witnesses:

FERNAND CHARROZ,
ANTOINE LAVOIS.
